UNITED STATES PATENT OFFICE

CHARLES FISHER, OF NEWARK, NEW JERSEY, ASSIGNOR TO THE AUTOMATIC RECORDING SAFE COMPANY, OF CHICAGO, ILLINOIS, A CORPORATION OF ILLINOIS

SAVINGS BANK

Application filed May 24, 1928, Serial No. 280,231, and in Great Britain April 24, 1928.

This invention relates particularly to savings banks having a form simulating a book; and the primary object of the invention is to provide a thoroughly practicable construction which can be manufactured easily and at small cost and which is staunch and reliable.

According to the present invention, provision is made for interlocking connections between the extremities of the arms of the U-shaped closure and an internal reinforcing member with which the back of the savings bank is provided.

The present invention is in the nature of an improvement upon the savings bank described in my pending application Serial No. 220,222, filed September 17, 1927.

The invention is illustrated in the accompanying drawing, in which—

20 Fig. 1 is a perspective view of a savings bank embodying the invention; Fig. 2, a plan sectional view on an enlarged scale; Fig. 3, a transverse section taken as indicated at line 3 of Fig. 2; and Fig. 4, a perspective view of 25 the removable closure which in the assembled structure corresponds with the edges of the leaves of a book.

In the construction illustrated, A designates the main body of the casing which corresponds with the sides and back of a book; B designates a removable closure which corresponds with the edges of the leaves of a book; and C designates a bolt, or locking-bar, 30 slidably mounted in the closure B.

35 The body A of the casing comprises a sheet of suitable material, preferably a thin sheet of hard fibre which is so formed as to provide a back 1 and sides 1^a; plates 2 disposed adjacent the inner surfaces of the sides 1^a; and 40 spacing-posts 3 uniting the sides 1^a and inner plates 2 in the manner shown in Fig. 3. As there shown in dotted lines, the posts have reduced end-portions 3^a extending through perforations in the side-members and plates 45 and spun, or riveted, at the outer surfaces of the walls 1^a. The posts thus have shoulders at 3^b which bear against the inner surfaces of the plates 2. The plates 2 may be of hard fibre, if desired.

50 The plates 2 serve to reinforce the side-

walls of the body A. They are of smaller dimensions than the side-walls, or plates, of the body A, and their end edges 4 are adapted to serve as guides for the closure in the assembling operation.

The body A preferably has applied thereto a covering 5 of suitable fabric, such as cloth, paper, leather, or the like; and preferably pads 6 are introduced between the covering and the side-walls of the casing. The margins 5^a of the covering are turned in about the edges of the U-shaped body of the casing and cemented to the inner surfaces, as will be understood from Fig. 3.

The plates 2 of the casing are connected by 65 guard-studs 7 which are disposed a little back of the front end-posts 3.

The closure B is of U-form, having the longitudinal edge-member 8 and end-members 8^a, as shown in Fig. 4. The U-shaped closure is of channel-form cross-section and its longitudinal member 8 houses the 70 slidable locking-bar C. Both of these parts preferably are made of strips of sheet brass stamped into suitable form, and the outer surface of the closure is in practice given a finish resembling the gilt edges of the leaves of a book.

The locking-bolt C comprises a strip which has its intermediate portion struck up or embossed to provide a wall 9 and flanges 9^a. The flanges 9^a are turned towards the main wall of the member 8 of the closure. Near the ends, the locking-bar is flattened as indicated at 9^b, and the extremities are turned backwardly as indicated at 9^c, and then at right angle 80 thereto as indicated at 9^d. The points 9^d extend in the same direction and afford hooks which are adapted to engage the front end-posts 3. The flattened portions 9^b are confined between guide-posts 10 and the main 85 wall of the member 8 of the closure, as will be seen from Fig. 2. A spring 11 serves to throw the locking-bar to locking position. This spring has one end secured to a flange of the closure in any suitable manner and has 90 the other end bearing against the shoulder 12 of the locking-bar C.

The key barrel 13 is rotatably confined between the member C and the main wall of the member 8 of the closure.

One of the end-members 8^a of the closure is provided with a coin-slot 14 which is equipped with a slot-guard 14^a which need not be described in detail. Adjacent the coin-slot is 5 a perforation 15 through which bills may be introduced.

It will be noted from Fig. 2 that the members, or posts, 7 serve to guard the hook-portions 9^a of the locking-bar, against tampering, as by inserting an implement through 10 the coin-slot 14, or bill-hole 15.

The coin-slot device includes a plate 16 which is provided with a slot and which is secured in position by means of clenching 15 lugs 17 formed integrally with the member 8^a. The plate 16 is equipped at one end with an inwardly extending piece 16^a which serves as a guard adapted to prevent coins from getting back of the adjacent end of the locking-bar. The portion 9^a of the locking-bar is 20 provided with a slot 18 through which the projection 16^a may extend when the locking-bar is retracted.

The locking-bolt C is provided at an intermediate point with laterally extending lugs 19 which are engaged by lugs 20 struck inwardly from the flanges of the member 8 of the closure. These lugs serve as guide-lugs and prevent the locking-bar from being 25 sprung inwardly away from the main wall of the member 8.

In accordance with the present invention, the flanges of the end-members 8^a are provided at their free extremities with slots 8^b 35 which engage flanges with which an internal back-reinforcing plate 21 is provided at its ends. The plate 21 is in the form of a narrow strip which extends a little short of the full length of the back and which is secured to 40 the back 1 by means of rivets 21^a. The end-portions of the bar 21 are turned forwardly to provide interlock flanges 21^b which are interlockingly engaged by the slots 8^b when the closure C is inserted to close the savings 45 bank. Thus, it is impossible to insert an implement at the extremities of the end-members 8^a for the purpose of springing the end-members outwardly.

It may be remarked also that the edges of 50 the internal reinforcing plates 2 not only serve as guides for the closure, but they also prevent the insertion of an implement between the edge of the closure and the side-wall of the savings bank.

55 The construction described is simple, easily manufactured, durable, and the product presents an exceedingly neat appearance. The guard-posts 7 prevent the unauthorized manipulation of the locking-bar as by means 60 of a button-hook, or other implement.

The foregoing detailed description has been 65 given for clearness of understanding only, and no unnecessary limitations should be understood therefrom.

What I regard as new, and desire to secure by Letters Patent, is:

A book-form savings bank comprising a U-shape casing having its side-walls equipped at their inner surfaces with reinforcing plates; an internal reinforcing strip secured to the back of said casing and having forwardly turned extremities affording interlock flanges; and a U-shape closure corresponding with the edges of the leaves of a book, said closure having inturned flanges abutting against the edges of said reinforcing plates, the extremities of said flanges being provided with slots interlockingly engaging the flanges of said reinforcing strip.

CHARLES FISHER.
